UNITED STATES PATENT OFFICE.

JOSEPH STRETCH AND JAMES E. CROSSLEY, OF EAST ORANGE, NEW JERSEY.

FAUCET.

SPECIFICATION forming part of Letters Patent No. 715,622, dated December 9, 1902.

Application filed February 26, 1902. Serial No. 95,700. (No model.)

To all whom it may concern:

Be it known that we, JOSEPH STRETCH and JAMES E. CROSSLEY, citizens of the United States, residing at East Orange, in the county 5 of Essex and State of New Jersey, have invented certain new and useful Improvements in Faucets, of which the following is a specification.

Our invention relates to improvements in 10 faucets; and the main object of our invention is the provision of a simple, durable, and inexpensive construction of faucet, as will appear in the following description thereof.

To attain this end, our invention consists 15 of a faucet embodying novel features of construction and combination of parts, substantially as disclosed herein.

In the accompanying drawings, Figure 1 is 20 a side elevation of the entire construction. Fig. 2 is a central sectional view thereof. Fig. 3 is an enlarged bottom plan view of the stopper or plug.

Referring to the drawings, A designates the body of the faucet, which is provided 25 with the exteriorly-screw-threaded and shoudered end B for attachment to the water-supply. The outer end C is at substantially right angles to the body and is provided with the interior screw-thread, in which is adapted to 30 fit the detachable seat and core-sleeve D, provided with the central opening or channel E and the lower socket F, which is provided with the depressed annular ring G at its top. This sleeve is also provided with the inclined 35 slot or opening H, the purpose of which will appear later. Mounted slidably in the socket of the sleeve is the core or water-passage J, which is provided with the annular ring or 40 projection K to correspond with the annular ring of the sleeve. Formed integral with this core and projecting upward through the opening of the sleeve is a stem L, which has mounted thereon the hard-rubber or aluminum plug or valve M, provided with the globular upper end N and the lower grooved end O, this plug being adapted to control the exit of the water through the central opening of the sleeve. In order to hold the plug upon 45 the stem, we provide the metal cap P and the nut Q, which clamps the plug upon the stem, so that the lower end thereof abuts against the upper portion of the core. Pro-

vided in one side of the core is a screw-threaded socket R, in which is adapted to be secured the handle S, which is guided in its 55 movements as the same is pushed from one side to the other by means of the inclined slot of the sleeve.

From the foregoing description, taken in connection with the drawings, it is evident 60 that we provide a faucet which is thoroughly efficient and practical in construction and operation, and as we have described the construction thereof and in order to have it more thoroughly understood we will proceed to describe 65 the operation.

When the faucet is closed, it assumes a position as shown in Fig. 2, the handle being directly in line with the body of the faucet. If the handle be turned, the slot in the sleeve 70 forces the core to slowly rise, and consequently the valve or plug, thus allowing the water to pass through the opening of the sleeve between its side and the grooves of the valve.

It will be noticed that we have shown the 75 lower end of the sleeve threaded, this being done in order that a hose may be attached thereto.

It will thus be seen that in this construction of faucet no packing is used, that only 80 one opening is necessary, that the only part of the faucet which will be subjected to great wear is the hard-rubber plug or valve, that a new one of these practically produces a new faucet, and that the parts of the faucet can- 85 not get loose or rattle, as the parts fit so snugly together.

What we claim as new, and desire to secure by Letters Patent, is—

In a faucet, the combination of a body having an internal screw-threaded exit, a detachable sleeve having a reduced threaded upper end adapted to engage the screw-threads of the exit and provided with a central channel having a valve-seat in its upper end, said 90 sleeve being further provided with an enlarged socket having a depressed annular ring in its upper end and an inclined slot through one wall thereof, a core having an inwardly inclined upper edge rotatably mounted in the 95 socket of the sleeve and provided with a cross-piece over its upper end, a stem carried by the cross-piece and extending upward through the channel of the reduced portion, a valve 100

mounted on said stem and having a serrated elongated end mounted in said channel, an enlarged globular upper end which is adapted to normally seat upon the valve-seat in the 5 upper end of the sleeve, and a stem carrying a knob entering the slot of the sleeve and engaging the core and adapted to be moved in the slot to raise or lower the core.

In testimony whereof we affix our signatures in presence of two witnesses.

JOSEPH STRETCH.
JAMES E. CROSSLEY.
